ASSIGNORS TO THE CONSOLIDATED SAFETY VALVE COMPANY, OF BRIDGEPORT,
CONNECTICUT, A CORPORATION OF CONNECTICUT.

SAFETY-VALVE.

1,151,508.

Specification of Letters Patent. Patented Aug. 24, 1915.

Application filed August 19, 1914. Serial No. 857,584.

To all whom it may concern:

Be it known that we, FREDERICK C. BLANCHARD and ERNEST B. CROCKER, citizens of the United States, and residents of 5 Bridgeport, in the county of Fairfield and State of Connecticut, have invented new and useful Improvements in Safety-Valves, of which the following is a specification.

This invention relates to safety valves of 10 the type commonly used upon locomotive boilers.

The bodies of safety valves of this type as heretofore made ordinarily comprise a base casting having a screw threaded portion 15 by which the valve is secured or mounted in service, and a cylindrical spring casing or shell detachably secured to said base. It not infrequently happens in service installation, that the base casting is screwed 20 on to a bushing or nipple defective by reason of a broken or inaccurately cut thread, thus distorting the body, which distortion being transmitted to the valve seat, which is rigidly connected with said base, causes 25 leakage of the valve. It also frequently happens that when the valve is taken apart for repair, the cylindrical spring casing or shell becomes bent and thrown out of round, with the result that when it is again screwed 30 on to the base, distortion of the valve body results, which is transmitted to and distorts the valve seat causing the valve to leak. Damage of this character often cannot be 35 foreseen and avoided even by the exercise of extraordinary care and attention, and such damage has heretofore been a source of considerable annoyance and expense.

It is the object of this invention to provide a valve wherein effective means are 40 provided to prevent leakage of the valve by reason of distortion of the valve seat caused by strains or distortions transmitted thereto from the valve body.

The drawing hereto annexed is a view 45 partly in section and partly in elevation of a safety valve embodying our invention.

In the drawing the valve body is formed with a relatively heavy base A preferably of 50 hexagonal form and having the usual screw threaded inlet A'. Said base is further provided with an upwardly extending, relatively weak and yielding, tubular wall A² curved as shown and having a circumferential corrugation A³, the portion of said wall

above said corrugation being externally 55 screw threaded. Said base A is further provided with a relatively high, slender and yielding cylindrical inner wall A⁴ having a valve seat B for the valve C which is held upon said seat in the usual manner by the 60 spring D surrounding the valve stem E. F is the spring casing or shell having a cylindrical depending portion F' provided with a circumferential flange F² screw threaded to engage the screw threads on the wall A², 65 the bottom of said casing resting upon the corrugation A³ which forms a seat therefor.

G is the muffler hood mounted on the flange F³ of the spring casing F.

It will, we believe, be clear that if when 70 the valve is taken apart for repair the casing or shell F through accident or negligence is struck upon its lower edge or otherwise distorted and thrown out of round, any strains or distortions of the 75 valve body which result upon the screwing of said damaged casing on to the wall A², are to a great extent dissipated or absorbed by the relatively weak and yielding character of said wall and that such distortions as 80 pass said wall are effectively absorbed or rendered negligible by the heavy base A so that they are not transmitted to the valve seat. Similarly, strains or distortions arising at the bottom of the base A by reason of 85 the mounting of the valve upon a defective bushing or nipple are to a great extent dissipated or absorbed by the relatively heavy base, and such distortions as pass said base are absorbed by the relatively high and 90 yielding wall A⁴ so that there is no distortion of the valve seat and consequent leakage of the valve.

Our improved construction is simple, 95 easy and economically manufactured, and actual service has demonstrated that it effectively eliminates the trouble and expense heretofore solely attributable to the transmission of strains and distortions of the valve body to the valve seat.

100 We claim:

1. In a valve, a valve body comprising a base and a casing removably secured thereto, a valve seat connected with said base, and a relatively yielding connection between said 105 base and said casing adapted to absorb distortions of the valve body which would otherwise be transmitted to the valve seat.

2. In a valve, a valve body comprising a base and a casing removably secured thereto, a relatively yielding connection between said base and said casing, a valve seat, a relatively yielding connection between said seat and said base, said connections adapted to absorb distortions of the valve body which would otherwise be transmitted to the valve seat.
- 10 3. In a valve, a valve body comprising a base and a casing, a curved, relatively yielding tubular wall fast on said base and upon which said casing is removably secured, a cylindrical, relatively yielding inner wall provided on one end with a valve seat and rigidly connected with said base at its other end, said walls adapted to absorb distortions of the valve body which would otherwise be transmitted to the valve seat.
- 15 4. In a valve, a valve body comprising a base and a casing, a curved, relatively yielding tubular wall integral with said base and having a circumferential corrugation, said casing being removably secured to said wall, a cylindrical relatively high, and yielding inner wall provided on one end with a valve seat and rigidly connected with said base at its other end, said walls adapted to absorb distortions of the valve body which would otherwise be transmitted to the valve seat. 20 25 30

Signed by us at Bridgeport, Connecticut,
this eleventh day of August, 1914.

FREDERICK C. BLANCHARD.
ERNEST B. CROCKER.
